Attorney

UNITED STATES PATENT OFFICE.

EDWARD G. HURD, OF SENECA, KANSAS.

CLOTHES-RACK.

SPECIFICATION forming part of Letters Patent No. 335,073, dated January 26, 1886.

Application filed May 8, 1884. Serial No. 130,774. (No model.)

To all whom it may concern:

Be it known that I, EDWARD G. HURD, a citizen of the United States of America, residing at Seneca, in the county of Nemaha and State of Kansas, have invented certain new and useful Improvements in Clothes-Racks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to clothes racks; and it consists in the improvements hereinafter described, and pointed out in the claim, whereby a simple and cheap structure is secured, and one that may be readily converted from a stand-rack to a bracket device.

In the accompanying drawings, Figure 1 is a perspective view illustrating my improvement arranged as a stand-rack. Fig. 2 is a vertical section of Fig. 1. Fig. 3 is an inverted plan of a part of my improvement, and Fig. 4 is a detail view.

A B represent two parallel horizontal beams bolted together by bolts *a b*, the bolt *b* serving as a pivot for a leg, *c*. A vertical plate, *C*, has at its lower portion a shank-extension, *d*, which is clamped between the bars A B, and has pivotally attached to it by a bolt, *e*, two legs, *f g*, which are inclined from each side at right angles from the leg *c*, as clearly shown in Fig. 1. The upper ends of the legs *f g* are beveled to permit the inclination of the said legs, and afford them a bearing against the inner faces of the bars A B. The upper end of the leg *c* is likewise beveled for a like purpose to bear against the end of the transverse securing-bolt *e*. The plate *C* carries on its front face two projecting pins or studs, *h*, which are adapted to engage openings therefor in a second plate, *D*. This plate *D* carries a shelf, *E*, braced by a central

bracket, *F*. A curved wire or rod, *i*, is secured at its ends to the plate *D*, and extends around beneath the shelf *E*, as shown in Figs. 1, 2, and 3, and is supported at intermediate points by means of loops *j*, depending from the under side of the shelf. A series of arms, *I*, are all pivotally attached to the rod *i* by means of wire loops *k*, one end of each loop being embedded in the end of the bar *I* to form a loop at that portion of the bar, and the other end is embedded in the under face of the arm *I*.

When the bars *I* are in the position illustrated in Fig. 1, and by the horizontal bar, as seen in Fig. 2, they bear with their bottom faces upon the wire *i*, while their end portions bear against the under face of the shelf *E*. By pulling each bar *I* outward, and causing the wire *i* to engage the loop formed by the wire *k* at the end of the bar, the bar will thus be suspended in a vertical position, as illustrated in Fig. 2, thereby reducing the space occupied by the structure.

If it be desirable to dispense with the stand, the plate *D* can be readily removed from its engagement with the pins *h* and caused to engage like pins on a wall or side of a room, and thereby constitute a bracket.

The openings in the plate *D* are preferably contracted toward the loop, so that the disengagement of the pins *h* can be effected by lifting the plate *D* before removing the same.

I claim—

The combination, in a clothes-rack, of a plate, of a frame or support consisting of the bars A B and pivoted legs *a b c*, beveled as described, and a plate provided with a series of pivoted arms and removably secured to said support or frame, substantially as set forth.

In testimony whereof I have affixed my signature in presence of two witnesses.

EDWARD G. HURD.

Witnesses:

LEWIS KEELEY,
A. W. BURK.
